2,032,792

HAIR CLIPPER

Theodore Chulanovsky, Detroit, Mich.

Application May 8, 1933, Serial No. 669,830

19 Claims.

(Cl. 30—1)

My invention relates to a new and useful improvement in a hair clipper, and particularly one of the power driven type. It is an object of the present invention to provide a clipper in which

5 the clipper may be so adjusted and arranged as to represent the various types of clippers used for the different types of hair cuts.

It is another object of the present invention to provide a mechanism in which the clipper may 10 be instantaneously changed from an arrangement for cutting one style of hair cut to another arrangement for cutting another style.

Another object of the invention is the provision of a clipper whereby hair cutting or trimming may be effected without the use of other 15 clippers, scissors or combs.

Another object of the invention is the provision of a hair clipper so arranged and constructed as to be instantly changed from a clipping machine 20 into a combing machine and vice versa.

Another object of the invention is the provision of a hair clipper whereby the labor and time normally required in hair trimming may be reduced to a minimum.

25 Another object of the invention is the provision of an adjusting arrangement which may be easily and quickly moved to various positions for varying or regulating the depth of hair cut.

Another object of the invention is the provision 30 in a hair clipper of this class of means for forcing the hair to be cut into the clipper and for carrying it away from the clipper after the cutting operation.

Another object of the invention is the provision 35 in a clipper of this class of a hair pressing mechanism for pressing the hair to be cut into the clipper and carrying it away and removing the same from the pressing element after the cutting operation.

40 Another object of the invention is the provision of a device of this kind which will be simple in structure, economical of manufacture, durable, highly efficient in use, light and compact.

Other objects will appear hereinafter.

45 The invention consists in the combination and arrangement of parts hereinafter described and claimed.

The invention will be best understood by a reference to the accompanying drawing which 50 forms a part of this specification, and in which,

Fig. 1 is a front elevational view of the invention with parts broken away.

Fig. 2 is a sectional view taken on line 2—2 of Fig. 1.

55 Fig. 3 is a sectional view taken on line 3—3 of

Fig. 1 slightly reduced in size and illustrating one of the elements moved forwardly.

Fig. 4 is a sectional view taken on line 4—4 of Fig. 2.

Fig. 5 is a fragmentary sectional view taken on 5 line 5—5 of Fig. 2.

Fig. 6 is a view taken on line 6—6 of Fig. 2 slightly reduced.

Fig. 7 is a fragmentary sectional view taken on line 7—7 of Fig. 2.

Fig. 8 is a fragmentary side elevational view 10 illustrating an indicator used in the invention.

As shown in the drawing, the invention comprises a casing or housing having the bottom 15 82, the side walls 16 and 17 and the rear wall 15

82. Positioned within this casing is a rigid frame comprising the oppositely disposed vertically extended side rails 18 and 19, the top rail 20 and the bottom rail 21. A bearing boss 22 is mounted on the inner face of the bottom 15 and a bearing boss 23 is formed on the inner face of the top rail 20.

In hair clippers, as commonly constructed, there are generally two cutter plates which are movable relatively to each other. I have illustrated the invention used with a clipper having the stationary cutter plate 24, on the outer edge of which are formed the cutter teeth 33.

This cutter plate 24 is secured to the bottom wall 15 of the casing and in engagement with the outer surface thereof by screws 26 30 which also serve to secure a supporting plate or block 25 in engagement with the bottom 15 over the cutter plate 24.

A recess 27 is formed in the upper face of the plate or block 25, and a pivot stud 28 projects upwardly through the recess 35 27 to form a pivot pin for the actuating arm 29, which is pivoted thereon. A cover plate 30 is held in position to retain the actuating arm 29

on the pivot pin 28 by means of the spring washer 31 and the nut 32 which is threaded on the 40 reduced threaded end of the pin 28. This cover plate 30 is turned downwardly at its forward edge to engage a cutter blade 35 and press the same firmly against the cutter plate 24, with the proper degree of tension.

This movable cutter blade 35 is slidably positioned on the upper surface of the stationary cutter plate 24, this movable cutter blade 35 having at one edge the cutting teeth 34. Slots 36 are formed in the cutter blade 35 and extending into these slots 50

are extensions 37 carried by and projecting upwardly from the stationary cutter plate 24. Formed in the rear edge of the cutter blade 35 is a notch 38 in which engages a head 39 formed on the actuating arm 29. The rear end of the 55

arm 29 terminates in the upwardly angularly turned rearwardly directed forked members 40 so as to provide the space 41 in which engages a crank 42. This crank 42 is formed intermediate the ends of a shaft, one end 43 of which is journaled in the bearing boss 22 and the other end 44 of which is journaled in the bearing boss 23. Fixedly mounted on this shaft intermediate its ends is a gear 45 which meshes with a worm 46 formed on the shaft 47 which is journaled in the bearing 50 carried in the rear wall 82 of the casing. It is intended that the shaft 47 shall be driven by an electric motor through a suitable flexible shafting connection. The inner end 49 of the shaft 47 is journaled in the bearing 50 carried on the lower end of the bracket 51 which extends outwardly and downwardly from the upper rail 20 of the frame. The worm 46 also meshes with a gear 52 which is fixedly mounted on the shaft 53. This shaft 53 projects through the enlarged portion 55 of the frame rail 19 and is provided with the spacing collar 54. The shaft 53 projects through a housing 56 mounted on the outer surface of the casing wall 16. The outer end of the shaft 53 is journaled in a bracket 57 which is also mounted on the wall 16. Projecting into this housing 56 are the shafts 58 and 59, each of which extends transversely of the casing and projects through supporting plates 60 and 60', mounted on the walls 17 and 16. Fixedly mounted on the shaft 53 within the housing 56 is a pulley 61. A pulley 62 is fixedly mounted on the shaft 58 within the housing 56 and a pulley 63 is fixedly mounted on the shaft 59 within the housing 56. A belt, formed preferably from an endless spring 64, passes around over all these pulleys so that when the shaft 47 is rotated to effect a rotation of the shaft 53, all of the pulleys will be rotated, and since these pulleys are fixedly mounted on their respective shafts, the shafts 58 and 59 will also be rotated. It is obvious that while the shaft 47 is being rotated, the actuating arm 29 will be oscillated to effect a reciprocation of the movable cutter blade 35.

Fixedly mounted on the shaft 59 between plates 60 and 60' are discs 65 radiating outwardly from which are the arms 66. A presser plate 67 having an outer angularly turned edge 68 is fixedly mounted on a rod 70 which extends through an oppositely positioned aligning pair of arms 66. The shaft 59 is provided with an elongated collar 71 at that portion which lies between the discs 65, and mounted centrally on this collar is a ring 72 of yieldable material such as rubber and the like, and against which a rearwardly projecting tongue 73 formed on the rear edge of each of the plates 67 is adapted to normally engage. A spiral spring 69 coiled about the shaft 70 and engaging, at one of its ends, the discs 65 is adapted to normally retain the plates 67 locked to that position in which the tongue 73 will engage the ring 72. A cam bar 74 is provided with an angularly turned flange 76 which is attached to the side wall 16 of the casing. The cam bar overlies the forward end of the guard plate 77 which is positioned between and engages, at its opposite edge, the side walls 16 and 17 and which is provided on its inner surface with a layer 78 of felt or the like. The upper end of this guard plate is angularly turned as at 79 to lie substantially parallel to the bottom 15. The rear end of this angularly turned portion is suitably secured to the upper end of the back of the casing. As clearly shown in Fig. 2, the guard

plate 30 projects forwardly of and serves as a cover for the recess 38 and the slots 36, so that access of hair to these parts, which might result in clogging of the mechanism, is prevented. The guard plate 77 projects forwardly of and overlies a cover plate 79 having at its opposite edges the downwardly projected flange 80. The under surface of this plate 79 is provided with a layer 81 of felt or the like so as to afford a protective covering for the pivot pin and the actuating parts. Fixedly mounted upon the shaft 58 between the plates 60 and 60' is a cylindrical brush 83 which, when rotated, is adapted to engage the comb or tooth plate 84 which is secured to the forward edge of a cover which comprises the top 87 and the sides 88. A plate 89 is mounted between plates 60 and 60' to reinforce the construction and form a cover for the brush 83.

Mounted on the under surface of the bottom 15 of the casing, adjacent the forward end thereof, is an inverted U-shaped support 90, projecting outwardly from the forward side of which are the guide rods 91 which extend through the partitions 92 and 93 carried by a comb-forming regulating shoe comprising the bottom 96 and the oppositely disposed side walls 95 and the rear wall 94. The forward edge is provided with teeth 97. A spring 98 is connected at one end to the partition 93 and at its opposite end to the bottom 15 so as to normally resist slidable movement of this regulating guide shoe or comb forwardly from the position shown in Fig. 2. In Fig. 3 I have shown this guide shoe or comb-forming member pressed forwardly to its forwardmost position.

Mounted on the side wall 17 is a bearing 99 through which extends the rockably mounted stud or shaft 101, to the upper end of which is fixedly mounted the head 103, projecting outwardly from which is the finger grip 102. Fixedly mounted, at one end, on the lower end of the shaft 101 is a plate 104, the free end of which is angularly turned downwardly to provide the engaging portion 105 which normally lies in engagement with the outer surface of the rear wall 94 of the regulating guide shoe. A boss 106 is formed on the member 90 and threaded through this boss is an adjusting screw 107 which may be used to regulate the degree of rearward movement of the regulating shoe in response to the tension of the spring 98. As shown in Fig. 8, there are formed on the outer face of the left side wall of this regulating shoe, graduations 108, cooperating with the pointer 109 to indicate the various positions of the regulating guide shoe. These graduations are so arranged on this guide shoe that each will indicate the proper position of the regulating guide shoe for a certain definite type of hair cut. It is obvious that by exerting pressure of the finger grip 102 as to rock the shaft or stud 101, the regulating guide shoe may be pushed forwardly against the tension of the spring 98. When this pressing force is released from the grip 102, the regulating guide shoe will snap back into its initial position which would normally be into a position so as to engage the end of the adjusting screw 107.

In use, when the shaft 47 is set into rotation, the cutter blade 35 will be reciprocated. At the same time the pulley 61 will be rotated to effect a rotation of the shafts 58 and 59. As the shaft 59 is rotated, the pressure plates will successively be brought into engagement with the cam 74 so as to ride over, with a very slight clearance, the cutting teeth 34 on the cutter blade 35. As these

presser plates 67 move downwardly into position, they will press the hair to be cut into the teeth and as the presser plate continues to move rearwardly as the shaft 59 is rotated, the angularly turned edge 68 of the presser plate 67 will serve to convey the cut hair along the surface of the guard plate 77 and between the guide plates 75 until the hair is brought into contact with the rotating bristles or brush 83 which will serve to sweep them upwardly and rearwardly along the face of the guard plate 77 beneath the comb or cleaning plate 84 which will serve to clean or comb the hair from the bristles or brush 83. Thus the brush 83 serves to clean the cut hair from the presser plate 67 and the member 84 serves to clean the cut hair from the bristles 83. As a succeeding quantity of the hair is conveyed upwardly, it will be forced outwardly through the rear of the cover 87 sliding along the angularly turned portion 78 of the guard plate. It will be noted that when the presser members engage the hair and press it into the teeth of the clippers, the springs 69 are under tension so that as these presser plates 67 move rearwardly along the cam 74 and guard plate 77, they will be held in close engagement with the surfaces of these members by the tension of the springs 69. As the preser plate clears the brush 83, these springs will rock the presser plates 67 on their mountings until the tongue 73 engages the ring 72. This is a violent movement and in order to absorb the shock and prevent undue noise, the ring 72 is preferably made of rubber or some yieldable material.

35 Before the clipping operation is started, the operator adjusts the screw 107 to move the adjusting shoe to the proper position so that the pointer 109 will register with the proper graduation 108 which represents the proper position 40 for a particular type of hair cut. The operator then grabs the casing in the right hand, with his thumb on the gripping portion 102, and then clipping is proceeded with in the usual manner.

For trimming the hair bordering upon the naked parts of the neck, the operator brings the lower front end of the machine into engagement with the border line. That is, either the teeth of the cutter 24 or the comb teeth 97 will be brought into engagement with the skin of the head, depending upon the previous adjustment of the adjusting shoe which will be indicated by the pointer 109 on the graduations 108. Then the operator would coordinate the upward bodily movement of the machine on the scalp with the rocking of the machine upon the adjusting shoe as a pivot, so as to obtain the proper variation of length of angle of cut. When the machine is rocked on the adjusting shoe as a pivot, the front end of the machine would, of course, be disengaged from the skin of the head, and the free ends of the longer hair, which would overlie the cutters when the front end of the machine was in engagement with the skin of the head, would be cut off, thus giving the scalp the appearance of a shade increasing in darkness upwardly.

In order to observe the result of the trimming, the operator would remove the machine from the head and force the adjusting shoe outwardly into its forward position shown in Fig. 3 and, while the adjusting shoe is in the forward position, smooth the hair by means of the comb teeth 97 in the ordinary manner. In this manner the operator proceeds around the head, always starting from the naked parts of the head and mov-

ing the machine upwardly and angularly to the free ends of the hair.

This machine may be used in all instances of hair trimming where the use of scissors and comb is normally required. Before using the machine, 5 the operator would first thrust the adjusting shoe to its forwardmost position shown in Fig. 3 by exerting pressure on the finger grip 102, while holding the adjusting shoe in its forwardmost position by means of the thumb of the right hand. 10 The combing teeth 97 would then be thrust into engagement with the scalp, directed against the normal inclination of the hair so that these combing teeth 97 would serve to raise the hair prior to cutting in the same manner in which the 15 hair is ordinarily raised by the comb when the operator intends to use the comb and scissors for cutting purposes.

After the hair has been engaged with the combing teeth 97, the entire structure is then rocked on 20 the adjusting shoe as a pivot, this adjusting shoe resting against the scalp. The combing teeth 97 would then comb the hair outwardly until the proper length of the hair to be cut off projects above the teeth 97. This can be readily observed 25 by the operator. Thereupon the operator, while holding the adjusting shoe stationary on the head, would release the pressure on the finger grip 102 and allow the mechanism to ride forwardly on the adjusting shoe as a supporting 30 base, until the cutting teeth are in their normal positions relatively to the combing teeth. As the cutting teeth reach the uplifted hair, this hair will be pressed against the cutters by the presser plate 67 and thus the proper amount of upstanding hair cut off. Consequently the machine thus 35 is used by the operator to perform with one hand what is ordinarily performed by the operator through the use of two hands when using the scissors and comb.

It is believed obvious that the teeth 97 of the adjusting shoe, after the adjusting shoe has been moved to its forwardmost position, may be used to serve all of the purposes and functions of a comb in smoothing or lifting the hair.

These teeth 97 are so arranged relatively to the teeth 33 which are formed on the stationary cutter plate 24 as to lie in alignment therewith so that the slots between the teeth 97 register with the slots between the teeth 33, thus a sticking 50 of the hair between the comb and the lower cutter plate teeth 33 is prevented.

It is believed obvious that if an operator does not desire to use the adjustable features of this device, the mechanism may be used in the manner of an ordinary pair of clippers with the additional advantages of trimming the free ends of the hair and of cutting hair having an automatically operated hair conveyor which serves to convey the clipped hair from the teeth of the clippers.

While I have illustrated and described the preferred form of my invention, I do not wish to limit myself to the precise details of structure shown but desire to avail myself of such variations and 65 modifications as may come within the scope of the appended claims.

Having thus described my invention, what I claim as new and desire to secure by Letters Patent is:

1. A machine of the class described comprising: a supporting frame; a clipping mechanism mounted at one side of said frame; a rotatable member carried by said frame; a plurality of pressers mounted on and rotatable in unison with 75

5 said rotatable member, on the axis thereof for
pressing hair toward the clipping mechanism;
common means for rotating said member and op-
erating said clipping mechanism; and a cam sur-
5 faced engagement member for engaging the edge
of each of said pressers successively for prevent-
ing engagement of the same with the clipping
mechanism.

10 2. A machine of the class described comprising:
a supporting frame; a clipping mechanism
mounted on said frame; an arcuate guard plate
mounted on said frame and projecting over the
clipping mechanism; a rotatable member carried
15 by said frame; presser members mounted on and
rotatable in unison with said rotatable member
for pressing hair toward the clipping mechanism
and subsequent to the clipping of the hair for
delivering the same on to said guard plate; a
20 cleaning member for cleaning the clipped hair
from the presser members, said cleaning member
effecting a further travel of the clipped hair along
said guard plate; and common means for effect-
ing an operation of said clipping mechanism, a
25 rotation of said rotatable member, and an opera-
tion of said cleaning member.

30 3. A machine of the class described comprising:
a supporting frame; a clipping mechanism
mounted on said frame; an arcuate guard plate
mounted on said frame and projecting over the
clipping mechanism; a rotatable member carried
35 by said frame; presser members mounted on and
rotatable in unison with said rotatable member
for pressing hair toward the clipping mechanism
and subsequent to the clipping of the hair for
delivering the same on to said guard plate; a
40 cleaning member for cleaning the clipped hair
from the presser members, said cleaning member
effecting a further travel of the clipped hair along
said guard plate; common means for ef-
fecting an operation of said clipping mechanism,
45 a rotation of said rotatable member, and an op-
eration of said cleaning member; and a combing
mechanism for combing the hair from said clean-
ing member.

50 4. In a machine of the class described, a sup-
porting frame; an arcuate guard plate mounted
on said frame; a clipping mechanism mounted
on said frame below said guard plate; means co-
operating with said guard plate for forming a
55 chute for passage of the clipped hair therefrom;
moveable means for delivering the clipped hair
from the clipping mechanism to said chute and
engageable during movement through a pre-de-
termined position with said guard plate; and
55 common means for operating said clipping mech-
anism and said delivery means.

60 5. A machine of the class described, comprising:
a clipping mechanism; a frame for support-
ing said mechanism; a rotatable shaft; a plura-
lity of presser members; means for swingably
mounting said presser members on said rotatable
65 shaft; yieldable means for maintaining said
presser members normally projecting radially
outwardly from said rotatable shaft; and com-
mon means for operating said clipping mech-
anism and rotating said rotatable shaft.

70 6. In a machine of the class described a clip-
ping mechanism; and means associated with said
mechanism for combing and raising the hair in
front of said clipping mechanism; means for mov-
ing said combing means to various positions rel-
75 atively to said clipping mechanism; and a press-
ing mechanism for pressing the raised hair into
said clipping mechanism and cooperating with
the combing means for indicating the height of

raising of the hair and determining the height
of cut of the hair.

7. In a machine of the class described a clip-
ping mechanism; means associated with said
mechanism for combing and raising the hair in
front of said clipping mechanism; means for
moving said combing means to various positions
5 relatively to said clipping mechanism; and a
pressing mechanism for pressing the raised hair
into said clipping mechanism and co-operating
with the combing means for indicating the height
of raising of the hair and determining the height
10 of cut of the hair and means for adjusting said
mechanism for determining the amount of rais-
ing of said hair.

15 8. In a machine of the class described a clip-
ping mechanism; means associated with said
mechanism for combing and raising the hair in
front of said clipping mechanism; and means for
feeding the raised hair to the clipping mecha-
20 nism.

25 9. A machine of the class described comprising:
a supporting structure; a clipping mecha-
nism mounted at the forward end of said struc-
ture; an adjusting shoe slideably positioned be-
neath the forward end of said structure and
30 normally lying rearwardly of the forward edge
of said clipping mechanism and adapted for
slideable movement forward to project beyond
the forward end of said clipping mechanism for
engaging and raising the hair varying distances
35 prior to engagement of the hair with the clipping
mechanism; resilient means for normally retaining
said shoe in retracted position; a movable
pressing mechanism mounted on said structure
40 for pressing the hair, subsequent to the raising
of the same, into the clipping mechanism, said
pressing mechanism co-operating with said shoe
for indicating the height of raising of the hair;
means operable at will for sliding said shoe into
45 various outwardly projected positions, the posi-
tion of outward projection determining the
height of raising the hair; and guide members
carried by said structure for guiding said shoe
in its slideable movement.

50 10. A machine of the class described comprising:
a supporting structure; a clipping mechanism
mounted at the forward end of said structure;
an adjusting shoe having a curved base and slide-
ably mounted beneath the forward end of said
55 structure and normally lying rearwardly of the
forward edge of said clipping mechanism and
adapted for slideable movement forwardly to pro-
ject beyond the forward end of said clipping
mechanism for raising the hair prior to its en-
gagement with said clipping mechanism; a mov-
able pressing mechanism mounted on said sup-
porting structure and movable into position for
engaging the hair raised by said shoe and di-
recting the same into the clipping mechanism,
60 said pressing mechanism co-operating with said
shoe for indicating the height of the raising of
said hair and determining the height of cut of
said hair; resilient means for normally retaining
said shoe in retracted position; means operable
65 at will for sliding said base into various outwardly
projected positions, said shoe in its various out-
ward projections effecting a raising of the hair
various heights; and adjustable means for re-
taining said shoe in various forwardly projected
70 positions.

75 11. A machine of the class described comprising:
a clipping mechanism; a frame for support-
ing said mechanism; a rotatable shaft mounted
on said frame; a plurality of arms radiating out-
75

- wardly from adjacent each end of said shaft, corresponding arms at opposite ends being in alignment; a presser member swingably mounted between each corresponding pair of arms and rotatable in unison with said shaft for pressing the hair toward the clipping mechanism; and common means for operating said clipping mechanism and rotating said shaft.
12. A machine of the class described comprising a clipping mechanism; a frame for supporting said mechanism; a rotatable shaft mounted on said frame; a plurality of radiating arms mounted on said shaft adjacent each end thereof and rotating in unison therewith, corresponding arms at opposite sides of said shaft being in alignment; a presser member swingably mounted between each pair of arms for pressing the hair toward the clipping mechanism; common means for operating the clipping mechanism and rotating said shaft; resilient means for resisting swingable movement of said presser members on said arms in one direction; and means mounted on said shaft for limiting the swingable movement of said members in the opposite direction beyond a pre-determined distance.
13. A machine of the class described comprising a supporting structure; a clipping mechanism mounted on said structure; adjusting shoe slidably positioned beneath the forward end of said clipping mechanism and adapted for slidable movement to project beyond the end of said clipping mechanism, the forward edge of said shoe having teeth formed therein to simulate a comb, said teeth upon movement forwardly of said clipping mechanism engaging the hair for raising the same in front of said clipping mechanism; a pressing mechanism mounted on said structure and movable for engaging the raised hair and pushing the same into said clipping mechanism, said pressing mechanism co-operating with said shoe for determining the height of cut of the raised hair; and means accessible during the operating of the clipping mechanism for moving said shoe forwardly of said clipping mechanism to various positions, the movement of said shoe to various positions effecting, in co-operation with said pressing mechanism, the determination of the cut of the hair at various heights.
14. A machine of the class described comprising a supporting structure; a clipping mechanism on said structure; a slideable tooth bearing member, positioned beneath the forward end of the clipping mechanism and projectable to extend forwardly of the cutting teeth of said clipping mechanism; a rotatable shaft on said structure; means for rotating said shaft; a plurality of radially extending circumferentially spaced presser members carried by and rotatable in unison with said shaft for pressing the hair into said clipping mechanism, said tooth bearing member effecting a raising and a pushing of the hair into position for engagement by said presser members.
15. A machine of the class described comprising a supporting structure; a clipping mechanism mounted at the forward end of said structure; an adjusting shoe slidably positioned beneath the forward end of said clipping mechanism and having teeth on its forward edge and normally lying rearwardly of the forward edge of said clipping mechanism and movable to project forwardly of said clipping mechanism for engaging the hair prior to its engagement by said clipping mechanism; resilient means for normally retaining said shoe in retracted position; presser members movable to press the hair in a direction opposite to the direction of movement of the said shoe, the position of outward projection of said shoe co-operating with said presser members for determining the height of cut of the hair.
16. A machine of the class described comprising a supporting structure; a clipping mechanism mounted at the forward end of said structure; an adjusting shoe slidably positioned beneath the forward end of said clipping mechanism and having teeth on its forward edge and normally lying rearwardly of the forward edge of said clipping mechanism for engaging the hair prior to its engagement by said clipping mechanism; resilient means for normally retaining said shoe in retracted position, presser members movable to press the hair in a direction opposite to the direction of movement of the said shoe, the position of outward projection of said shoe co-operating with said presser members for indicating the height of raising of the hair by said shoe and determining the height of the cut.
17. A machine of the class described comprising a supporting structure; a clipping mechanism mounted at the forward end of said structure; an adjusting shoe slidably positioned beneath the forward end of said clipping mechanism and having teeth on its forward edge and normally lying rearwardly of the forward edge of said clipping mechanism and movable to project forwardly of said clipping mechanism for engaging the hair prior to its engagement by said clipping mechanism; resilient means for normally retaining said shoe in retracted position; presser members movable to press the hair in a direction opposite to the direction of movement of the said shoe, the position of outward projection of said shoe co-operating with said presser members for determining the height to which the hair is raised immediately prior to its passage into the clipping mechanism.
18. A machine of the class described, comprising: A supporting structure; a clipping mechanism on said structure; a rotatable member; presser arms pivotally mounted adjacent one of their ends circumferentially in spaced relation of said rotatable member; a cam forming member adapted upon rotation of said rotatable member to predetermined positions for separately engaging the ends of the presser arms and rocking the same on its pivot during the rotation of said rotatable member for effecting a travel of the presser arm in a plane projected over the clipping mechanism.
19. A machine of the class described, comprising: a supporting structure; a clipping mechanism on said structure; a rotatable member; presser arms pivotally mounted adjacent one of their ends circumferentially in spaced relation of said rotatable member; a cam forming member adapted upon rotation of said rotatable member to predetermined positions for separately engaging the ends of the presser arms and rocking the same on its pivot during the rotation of said rotatable member for effecting a travel of the presser arm in a plane projected over the clipping mechanism; and means for raising the hair to be clipped into the path of the presser arm while traveling in its own plane.
